ATTORNEY.

UNITED STATES PATENT OFFICE.

LESLIE J. LAMB, OF OAKLAND, CALIFORNIA.

ARTIFICIAL LEG.

Application filed November 18, 1926. Serial No. 149,094.

My invention relates to artificial legs for above-knee amputations and is directed especially to the knee joints thereof.

It is an object of my invention to improve upon artificial legs of the well-known tubular type to increase their strength and rigidity without appreciably altering their light weight. It is an object of my invention to overcome the objectionable quivering which occurs when a heavy man steps down from a curbing or other elevation, upon his artificial leg. It is an object of my invention to overcome the wobbling and feeling of instability and unsolidity which the wearer of the ordinary artificial leg is troubled with when arising from a sitting position.

It is a further object of my invention to alter the effective point of support of the lower leg relative to its pivot and to its center of gravity, to normalize the inclination of said lower leg at all times.

There must be auxiliary pivotal means connecting the lower leg to the leg-supporting harness in order to control the inclination of the lower leg, and it is an object of my invention to overcome the squeaks and noises which frequently are caused by this usual metallic connection. It is a further object of my invention to maintain this connection close to the main knee-hinge-pivot point, and to make its effective line of stress transmission as invariable as possible with altered leg inclinations.

Other and ancillary objects of my invention will be brought out in the following description, or will be suggested in the use of the device of my invention. Certain modifications from the device herein described in detail are possible within the purview of my invention, and therefore, I desire to be circumscribed only within the limits set up by the claims finally determining my invention.

Referring to the drawings:

Figure 1 is a composite side elevation and median vertical section of the knee portion of an artificial leg incorporating my improvements; the major part of the figure being broken away to disclose said section.

Fig. 2 is a composite front elevation and vertical section similar and at right angles to the view of Fig. 1. The plane and extent of section are indicated by the line 2-2 in Fig. 1.

Fig. 3 is a transverse sectional plan above the brace in the lower leg. The plane of section is indicated by the line 3-3 in Fig. 1.

Fig. 4 is a perspective view of the portion of the pivotal arm which incorporates the brace extending to the front wall of the lower leg.

The artificial leg consists of an upper limb portion 2 generally of hollow fibre adapted to receive the wearer's limb stump, and is hingedly connected to the lower leg 4, also generally of hollow fibre. For convenience of description, the front wall of the lower leg is differentiated by the reference character 6, and the rear wall thereof by the character 8. The upper and lower extremities of the leg are purely of conventional character and do not form part of my invention, which is an improvement directed to the knee portion of the leg. It will be understood that an artificial foot is attached to the lower extremity of the leg, and that the straps 10, 12, and 14 terminate above the artificial leg in a harness for attaching the artificial leg to the wearer's body.

The bottom 16, of the upper limb portion, is reduced in size to recess slightly into the lower leg 4, and carries the knee-hinge pin 18 journaled transversely therethrough. A pair of bearing lugs 20, 22 upstand one from each side of the lower leg 4, to receive the ends of the pin 18, and pivotally support the lower leg from this pin.

Means are customarily provided for controlling the pivotal position of the lower leg relative to the upper leg. A crank arm 24 is journaled on the pin 18 with its long arm curving into contact with the rear wall 8 of the lower leg, and to which it is secured by a bolt 26. The strap 12 leading from the suspender or shoulder harness which supports the leg, terminates in a stirrup 28, the lower bar 30 of which, is a pin for pivotally attaching the harness to the arm 24. It will be understood, that although the strap 12 should at all times be taut enough to hold the artificial leg to the stump when the wearer's weight is off the leg, yet by connecting the stirrup to the arm 24 abaxially of the main hinge pin 18, the lower leg may be pivotally moved somewhat by increasing or decreasing the tension of strap 12. The hole 32 in back of the pin 18 in the arm 24, was intended to receive the stirrup pin 30 for this purpose. A stop 34 on the arm 24, cooperates with the bottom of the upper limb portion at 36 to prevent reverse buckling of the knee joint.

By raising and lowering the harnessed

shoulder as he walked, the wearer might operate the lower artificial leg to simulate normal leg action. However, it is found that the normal tension of the strap 12 always 5 keeps the lower leg inclined backward somewhat, causing the toe to drag when walking.

While shifting of the weight in walking naturally causes the leg to incline backward at the desired time, the difficult thing is to 10 straighten the leg to rigid position. A further disadvantage I endeavor to overcome by my improvement is entailed in the fact that the hole 32 is spaced so far from the pivotal axis, that excessive shoulder motion is required to operate the lower leg.

I have provided means for attaching the stirrup 28 to the arm 24 in front of and very close to the main hinge pin 18, and I have purposely made this connection flexible and 20 non-metallic. A leather strap 38 is secured to front of the arm 24 by a screw 40. The upper end of the strap terminates in a loop 42 to receive the stirrup pin 30, and a wire 44 is looped horizontally around the strap 25 between the screw 40 and the loop 42, and is fixed at 32 to the arm 24. The wire 44 permits free inward flexing of the strap 38, but limits its outward movement. Thus the line of force action never moves far from the 30 hinge pin 18 no matter how far the lower leg is bent. A reinforcing bracket 46 is riveted to the arm 24 and has its outer end bowed to receive the depending looped end 48 of the strap 38. The bracket 46 is merely an attachment auxiliary to the single screw 40.

Looped straps 48 and 50 are riveted to opposite sides of the stirrup 28 and are adapted to receive the guy straps 10 and 14 for bracing the knee laterally to maintain the leg in a vertical plane.

The artificial leg is of light construction, and it is invariably found that the bearing lugs 20 and 22 sag enough to cause the arm 24 to transmit a certain amount of the wearer's weight to the rear wall 8 of the lower leg. This produces an objectionable unbalance, and which unbalance is a most important object of my invention to overcome. The situation is remedied by means of an auxiliary brace. A metal strip 52 is bent into an elliptic bow 54, and its ends are brought together into a yoke 56 which straddles and is riveted to the mid-portion of the arm 24. The bow terminates in contact with the front 55 wall 6 of the lower leg, and is attached thereto by a bolt 58. A diagonal strut 60 riveted between the strip 52, and the arm 24 completes

the reinforcing brace. It will readily be seen that the stress is distributed by this brace so that the wearer's weight is transmitted vertically through the knee joint without any tendency to buckle the leg or to cause wobbling or other insecurity.

I claim:

1. In combination with an artificial leg 65 comprising a tubular upper limb portion, a harness strap from said upper limb portion adapted to attach the artificial leg to the wearer's stump, a tubular lower leg, a hinge pivotally connecting the lower leg to said upper portion, a pivotal arm connecting the hinge pin to the rear wall of the tubular lower leg, a brace connecting the front wall of the lower leg to said arm, a flexible support secured to said arm in front of, immediately 70 adjacent, and partially concentric, to the hinge axis, and pivotal means connecting said support to said harness strap to control the inclination of the lower leg.

2. In combination with the knee hinge of 80 an artificial leg, a control arm pivoted about the pin of said hinge and having an end thereof fixed to the lower leg portion, an operating member for said arm secured thereto to extend upwardly therefrom forwardly of 85 said hinge pin, and means to maintain the effective lever arm of said operating member constant for the different angular relations of said leg portions.

3. In combination with the knee hinge of 90 an artificial leg, a control arm pivoted about the pin of said hinge, said arm having an end thereof fixedly related to the lower leg portion and the forward portion of the other end thereof cylindrically curved about the pivotal axis of the arm, and a flexible extension member for said arm fixed thereto to extend longitudinally of the upper leg portion and arranged to maintain an engagement with the cylindrically curved surface of said 95 second arm end.

4. In combination with an artificial leg comprising a tubular upper leg portion, a harness strap from said upper portion for securing the artificial leg to the wearer's leg 105 stump, a lower leg portion, a hinge pivotally connecting said leg portions, a control arm connecting the hinge pin to the lower leg portion, a flexible support secured to said arm in front of and partially concentric to the 110 hinge axis, and means connecting said support to said strap.

In testimony whereof I affix my signature.
LESLIE J. LAMB.
